UNITED STATES PATENT OFFICE

CHARLES H. FRANZ, JR., OF MILWAUKEE, WISCONSIN

LOCKING LEVER FOR LOOSE-LEAF BINDERS

Application filed August 8, 1930. Serial No. 473,817.

This invention relates to loose-leaf binders of the type embodying a sliding, locking bar carried by one of the covers for removably engaging headed studs or posts carried by the other cover and is an improvement over my pending application Serial No. 35,084 filed June 5, 1925.

Considerable difficulty has been experienced in properly grasping the locking bar to permit the convenient sliding thereof into and out of this locked position.

It is therefore one of the primary objects of my present invention to provide a handle or finger piece on one end of the locking bar, so arranged as to permit the same to be readily engaged by the operator and to effectively permit the easy sliding of the locking bar.

Another salient object of my invention is the provision of an operating finger piece on the locking bar extending substantially parallel to the covers of the binder and having a portion thereof extending above the plane of the loose-leaves, whereby the fingers of the operator can be placed between the leaves and the top cover for engaging said finger piece, thereby readily permitting the actuation of the locking bar.

With these and other objects in view the invention consists in the novel construction, arrangement and formation of parts, as will be hereinafter more specifically described, claimed, and illustrated in the accompanying drawings, in which:

Figure 1 is a fragmentary end elevation of a binder showing my improved manipulating finger piece incorporated with the locking bar thereof and illustrating the method of actuating the same.

Figure 2 is a fragmentary transverse section through the binder illustrating the arrangement of the headed post and the locking bar relative to one another.

Figure 3 is a longitudinal section taken on the line 3-3 of Figure 2 looking in the direction of the arrows illustrating the posi-

tion of the finger piece relative to its adjacent cover.

Referring to the drawing in detail wherein similar reference characters designate corresponding parts throughout the several views the letter A generally indicates a loose-leaf binder which is of the type shown in my mentioned application and thus the binder will not be described in detail, but it is to be noted that the same includes the covers 5 and 6 having the rigid back pieces 7 and 8 respectively. The cover 5 carries the headed adjustable posts 9 having the heads 10 which are received in the slots 11 formed in one edge of the tubular sheath 12 carried by the cover 6. The sheath 12 slidably receives the locking bar 13 for the heads 10 of the adjustable posts 9 and by referring to Figure 3 of the drawing it can be seen that the locking bar is provided with bayonet-shaped slots 14 for receiving the headed ends 10 of the post.

In one position of the locking bar 13, the transverse portions of the bayonet-shaped slots 14 register with the slots 11 in the sheath 12. When the locking bar is in this position the headed ends 10 of the post 9 can be readily introduced into the sheath and when the locking bar 13 is moved to its locked position as shown in Figure 3 of the drawing the covers 5 and 6 are held in a locked assembled position. Thus by sliding the locking bar 13 the covers can be connected or disconnected.

As in the usual construction the adjustable posts 9 receive the perforated loose-leaves 15 which are to be held between the covers 5 and 6.

In accordance with my invention I provide novel means for facilitating the sliding of the locking bar 13 in its sheath 12, and this means embodies a finger piece 16 formed on one end of the said locking bar 13. The finger piece 16 is formed integral with the locking bar and is connected thereto by means of the twisted shank portion 17 and this shank por-

tion 17 is so twisted as to permit the extending of the finger piece 16 in the same direction as the covers 5 and 6 and in a direction parallel with the loose-leaves 15. The finger spaced at all times from the leaves 15 and a portion thereof extends outwardly of the uppermost leaf. Thus the finger piece is disposed between a plane perpendicular to the longitudinal edges of the cover 6 of the 10 binder and the upper edge portions of the leaves 15.

By this arrangement and construction the finger of the operator can be readily inserted between the cover 6 and the loose-leaves 15 15 for engaging the finger piece, which will permit the easy shifting of the finger piece laterally and the consequent operation of the locking bar.

It is obvious that if the finger piece 16 were 20 depended inwardly between the planes formed by the opposite edges of the stack of leaves that difficulty would be experienced in placing the finger between the loose-leaves and the finger piece, but by having the finger piece extending in the direction parallel to the cover with a portion thereof above the leaves 15 the same can be conveniently engaged and actuated.

Changes in details may be made without 25 departing from the spirit or scope of this invention.

I claim:

1. In a loose-leaf binder, a pair of covers, headed posts carried by one of the covers and 30 adapted to receive loose-leaves, a sheath carried by the other cover receiving the heads of the posts, a locking bar slidable in the sheath for the post, and a manipulating finger piece on one end of said locking bar ex- 35 tending parallel to said covers and leaves and having a portion thereof arranged between a plane perpendicular to the longitudinal edges of the cover of the binder and the upper edge portions of the leaves to permit the convenient engaging thereof by the finger of the operator.

2. In a loose-leaf binder, a pair of covers, headed posts carried by one of the covers and adapted to receive loose-leaves, a sliding locking bar carried by the other cover for the 40 headed ends of the posts, and a manipulating finger-piece formed on one end of the locking bar and extending at right angles to the longitudinal edges of the locking bar parallel to the covers and leaves, a portion of said finger piece being normally arranged between a plane perpendicular to the longitudinal edges of the cover and the upper edge portions of the leaves.

3. In a loose-leaf binder, a pair of covers, headed posts carried by one of the covers and adapted to receive loose-leaves, a substantially flat slidable locking bar carried by the other cover for engaging the headed ends of 45 the posts and one end of said locking bar be-

ing twisted to form a manipulating finger piece, the transverse body of which is disposed at right angles to opposite sides of the locking bar with a portion of said finger piece being normally arranged outwardly of the 70 loose-leaves and inwardly of the adjacent cover.

In testimony that I claim the foregoing I have hereunto set my hand at Milwaukee, in the county of Milwaukee and State of Wisconsin. 75
